UNITED STATES PATENT OFFICE.

PHILIP JACOB MEAHL, OF BAYONNE, NEW JERSEY.

PAPER-FEED MECHANISM.

969,295.

Specification of Letters Patent. Patented Sept. 6, 1910.

Application filed September 23, 1909. Serial No. 519,121.

To all whom it may concern:

Be it known that I, PHILIP JACOB MEAHL, a citizen of the United States, and a resident of Bayonne, in the county of Hudson and State of New Jersey, have invented certain new and useful Improvements in Paper-Feed Mechanism, of which the following is a specification.

This invention relates to improvements in paper feed mechanism such as is used for feeding paper in machines for making perforated music rolls.

The object of my invention is to provide a new and improved machine of this kind which is simple in construction, reliable in action, feeds the paper positively and uniformly and holds the several superimposed layers of paper firmly and securely while they are being perforated by the perforating machine.

In the accompanying drawings in which like letters of reference indicate like parts in all the figures: Figure 1 is a plan view of my improved paper feed mechanism, parts being broken away. Fig. 2 is a vertical longitudinal sectional view of the same. Fig. 3 is an enlarged detail plan view of parts; partly in action. Fig. 4 is a vertical sectional view through the parts shown in Fig. 1. Fig. 5 is a vertical transverse sectional view through the paper feed mechanism. Fig. 6 is a detail plan view of the clamping jaw.

In the ends of two parallel horizontal frame bars 1 united by cross bars 26 two parallel shafts 2 and 3 are mounted to rotate and each carries at each end a sprocket wheel 4, and over each two sprockets at each side of the frame formed by the bars 1 an endless sprocket chain 5 is passed, said chains being connected at regular intervals by cross bars 6. In each end of each bar 6 a bolt or pin 7 is mounted to turn axially and to be movable in the direction from the top to the bottom of the bar and reversely. The lower or inner end of each pin 7 is slightly rounded and above such rounded end an angle arm or L-shaped arm 14 is secured on the pin and between said arm and a suitable washer on the inner side of the bar 6 a helical spring 8 surrounds the pin and serves to draw the same

lengthwise inward. On the outer end of each pin 7 a paper clamping jaw 9 is secured which has an arm or extension 10 beyond the pin and from the under side of this arm or extension a locking pin 11 projects which can pass into holes 12 or 13 in the upper surface of the bar 6 according to the position of the jaw.

A cam track 15 is formed on the extension 60 end edge of each side bar at that end of the machine first reached by the paper, that is a series of superimposed layers of paper represented by 16 in the drawings, and on the upper surface of each side bar 1 and at the 65 upper end of said cam track an upright or beveled or tapering cam projection 24 is formed along the inner edge of the bar 1. At the opposite end of each bar 1 a like cam projection 17 is formed on the upper surface 70 of the bar along the outer edge of the bar and at said projection a flat plate 18 is secured on the top of each bar 1 and provided at its inner end with a beveled cam face 19.

Side plates 20 covering the top parts of the sprocket chains 5 are supported by arms 21 mounted loosely on the shafts.

The shaft 2 carries a worm wheel 22 engaged by a worm 23 on a driving shaft 27.

The operation is as follows: The paper is moved in the direction of the arrows Figs. 3 and 4. As the pins 7 with the lower rounded ends ride upon the cam tracks 15 the pins are raised and as one end of the angle 85 arm 14 on the pin encounters the cam projection 24 the pin is given axially a quarter turn and the clamping jaw 9 on said pin, which has been lifted above the plane of the uppermost layer of paper by the cam 90 track is turned 90° and extends inwardly at right angles to the edge of the paper and over the edge part of the paper and when the lower end of the pin has reached the inner end of the horizontal part of the cam 95 track 15 and slides off, the expanding spring 8 forces the clamping jaw downward suddenly and firmly upon the paper which is now firmly and securely gripped between the jaw and the upper surface of the bar 6 100 and the jaw is locked in position by the locking pin 11 which has entered the hole 13.

These movements take place for both clamping jaws on each bar 6 as the bar in its travels arrives in position above the shaft 3 and the parts remain in these positions 5 during the time the bar travels from the shaft 3 to the shaft 2. Shortly before the pins 7 arrive above the shaft 2 their lower ends ride upon the bevel 19 of the plate 18 and are raised and thereby the clamping 10 jaws 9 are lifted off the paper 16 and immediately thereafter their angle arms 14 encounter the cam projections 17 whereby the pins 7 are given a quarter turn and the clamping jaws 9 are swung outward 90° 15 and beyond the edge of the paper and parallel therewith. The parts remain in these positions until the pins 7 slide off the outer ends of the flat plates 18. The springs 8 expand and pull the jaws 9 upon the upper 20 surfaces of the bars 6 and the jaws are locked in place by the pins 11 entering the holes 12 in the outer faces of the bars. The jaws remain in these positions until the pins 7 again arrive at the cam tracks 15 and so 25 on. The jaws of three cross bars 6 grip the paper at the same time and the jaws are not applied upon the paper until they have arrived above the upper surface of the paper so that there is no liability of the turning or 30 swinging jaws mutilating the surface or edge parts of the paper.

Having described my invention what I claim as new and desire to secure by Letters Patent is:

35 1. In a paper feed mechanism, the combination with endless chains, mechanism for moving them and cross bars uniting them, of clamping jaws mounted on the bars and means for alternately lifting the jaws in the 40 direction from the bars and lowering them in the direction toward the bars and means for turning the jaws when raised, substantially as set forth.

2. In a paper feed mechanism, the combination with endless chains, mechanism for moving them and cross bars uniting them, of clamping jaws mounted on the bars and means for alternately lifting the jaws in the direction from the bars and lowering them 50 in the direction toward the bars and means for turning the jaws when raised, alternately in the direction of the length of the bars and at right angles thereto, substantially as set forth.

55 3. In a paper feed mechanism, the combination with endless chains, mechanism for moving them and cross bars uniting them, of clamping jaws mounted on the bars and means for alternately lifting the jaws in 60 the direction from the bars and lowering them in the direction toward the bars and means for turning the jaws when raised, alternately in the direction of the length of the bars and at right angles thereto, and

means for temporarily locking the jaws in 65 position after each adjustment, substantially as set forth.

4. In a paper feed mechanism, the combination with endless chains, mechanism for moving them and cross bars uniting them, 70 of clamping jaws mounted on the bars and means for alternately lifting the jaws in the direction from the bars and lowering them in the direction toward the bars and means for turning the jaws when raised, alternately 75 in the direction of the length of the bars and at right angles thereto and springs acting on the jaws to press them toward the outer surface of the bars, substantially as set forth.

5. In a paper feed mechanism, the combination with sprocket wheels and endless chains, of cross bars uniting the chains, clamping jaws on the bars, mechanism for lifting the jaws when the chains ride upon the one set of sprocket wheels and means for 85 lifting the jaws and turning them outward when the chains pass off the other set of sprocket wheels, substantially as set forth.

6. In a paper feed mechanism the combination with endless chains, of mechanism 90 for moving them and cross bars uniting them, of clamping jaws mounted on the bars, frame bars between the sprocket wheels and cams on said frame bars for raising and turning the clamping jaws, substantially as 95 set forth.

7. In a paper feed mechanism, the combination with sprocket wheels, of endless chains passed over them, bars uniting the chains, a pin mounted on the end of each 100 bar to turn and to move through the bar, a clamping jaw on the outer end of which pin, an L shaped arm on the end of each pin, springs on the pins for pressing the jaws upon the outer surfaces of the bars, a fixed 105 frame and cams on said frame for lifting and turning the pins, substantially as set forth.

8. In a paper feed mechanism, the combination with sprocket wheels, of endless 110 chains passed over them, bars uniting the chains, a pin mounted on the end of each bar to turn and to move through the bar, a clamping jaw on the outer end of each pin, an L shaped arm on the end of each pin, 115 springs on the pins for pressing the jaws upon the outer surfaces of the bars, a fixed frame and cams on said frame for lifting and turning the pins, locking pins projecting from the underside of the jaws, the 120 bars being provided in their outer surfaces with two holes into which said locking pins can enter, substantially as set forth.

9. In a paper feed mechanism, the combination with endless chains, mechanism for 125 moving them and cross bars uniting them, of clamping jaws mounted on the bars and means for alternately lifting the jaws in the

direction from the bars and lowering them in the direction toward the bars, and means for turning the jaws when raised, locking pins projecting from the underside of the 5 jaws, the bars being provided in their outer surfaces with two holes into which said locking pins can enter, substantially as set forth.

Signed at New York in the county of New York and State of New York this 21st day of Sept. A. D. 1909.

PHILIP JACOB MEAHL.
